ZERO RETURN FOR ELECTROMECHANICAL
INTEGRATORSSamuel L. Fagin, New York, N. Y., assignor to
Engineering & Research Corporation, River-
dale, Md., a corporation of Maryland

Application October 20, 1949, Serial No. 122,485

1 Claim. (Cl. 235—144)

1

This invention relates broadly to electromechanical integrators of the type which operates to displace an output shaft from a zero position by an amount which is a function of the integral of an input voltage. It has been found that in the use and operation of such integrators it is very difficult and time-consuming to return the output shaft to zero position after the completion of a problem, and no means other than manual have heretofore been known to effect this return operation.

It is therefore the object and result of this invention to provide means for returning the output shaft of an electromechanical integrator to zero position after completion of a problem and in order to apply the integrator to a new problem.

An electromechanical integrator embodying the zero-return means according to my invention is disclosed in the single figure of the drawings. The integrator disclosed in this figure comprises a source of alternating or direct current 2 connected through switch 4, resistance 6 and amplifier 8 to a motor 10, the armature of which is connected through shaft 11 to a generator 12. Voltage generated by generator 12 is supplied through resistance 14 to the connection between resistor 6 and the input side of amplifier 8. The shaft 11 is connected through reduction gearing 16 to an output shaft 18, the displacement of which from a zero position is proportional to the integral of the input voltage supplied by source 2.

The foregoing apparatus comprises a conventional electromechanical integrator which operates in the following manner. An input voltage which is to be integrated, and which may be alternating current or direct current, is supplied to resistance 6 and is added algebraically to voltage from generator 12 by means of the resistors 6 and 14. The amplification of the amplifier is so great as to keep the motor and generator running at a speed such that the voltage output of the generator very closely cancels the input signal voltage. The displacement of the potentiometer shaft 18 from zero position will therefore be a measure of the integration of the input voltage, all in accordance with known practice.

By this invention I provide means for returning the output or potentiometer shaft 18 to zero position after it has been displaced therefrom in the integration of an input voltage. Such means comprise a potentiometer 20 the contact arm 22 of which is driven by the output shaft 18 over the potentiometer resistance 24. The opposite end terminals of the resistance are connected to two sources of voltage which are of opposite po-

larity, if D. C., or of opposite phase if A. C., the center point 26 of the resistance accordingly being at zero potential. The contact arm 22 is connected through switch 28, resistance 30 and amplifier 8 to the motor 10 and the generator 12 is connected through resistance 14 to the connection between resistance 30 and the amplifier, whereby voltage at the contact arm 22 due to its displacement from the zero potential point of potentiometer resistance 20 is added algebraically to voltage from generator 12 by means of the resistors 30 and 14.

In the operation of an integrator embodying my invention it will be assumed that the operation of the integrator has caused displacement of the potentiometer shaft and contact arm clockwise from the zero potential point of resistance 24, as shown in the drawing. During this integration, switch 4 was closed and switch 28 was open. If it is now desired to return the potentiometer shaft to zero position the switch 4 is opened and switch 28 is closed. Voltage at the contact arm due to its displacement from the zero potential point of resistance 24 will now be supplied to resistor 30 and will be added algebraically to voltage generated by generator 12 and appearing across resistor 14. The motor will accordingly be rotated in such a direction as to return the output shaft 18 of the integrator and the movable contact 30 of the potentiometer to zero position where it will remain until the integrator is again operated.

While I have described and illustrated one embodiment of my invention, it will be apparent to those skilled in the art that other embodiments, as well as modifications thereof, may be made without departing in any way from the spirit or scope of the invention for the limits of which reference must be had to the appended claim.

40 What is claimed is:

In an electromechanical integrator of the type in which a shaft is displaced proportionally to the time integral of an incoming voltage, a motor, a shaft connected to said motor, a generator connected to said shaft, means connecting the output voltage of said generator to said motor, a first potential source, means normally connecting said first potential source to said motor for integration, means for returning said shaft to zero position comprising a second potential source, a potentiometer connected to said second potential source whereby a zero potential point is established on said potentiometer, a contact arm on said potentiometer connected to said shaft, means for connecting said contact

arm to said motor and means for disconnecting said first potential source from said motor whereby the potential at the contact arm is combined with the voltage output of the generator to control said motor to return said shaft to zero position and said contact arm to said zero potential point.
